UNITED STATES PATENT OFFICE.

CHARLES B. POST, OF NEW LONDON, OHIO, ASSIGNOR OF ONE-HALF TO
JOHN D. OL'COTT, OF SAME PLACE.

WIND-ENGINE.

SPECIFICATION forming part of Letters Patent No. 269,320, dated December 19, 1882.

Application filed October 14, 1882. (No model.)

To all whom it may concern:

Be it known that I, CHARLES B. POST, of New London, in the county of Huron and State of Ohio, have invented certain new and useful 5 Improvements in Wind-Engines; and I do hereby declare the following to be a full, clear, and exact description of the invention, such as will enable others skilled in the art to which it pertains to make and use the same.

10 My invention relates to wind-engines; and it consists in the parts and combination of parts, as will be hereinafter fully set forth and claimed.

In the drawings, Figure 1 is a view in front 15 elevation of my wind-wheel. Fig. 2 is a vertical section taken through the wind-wheel, and also through a portion of the supporting framework and turn-table. Figs. 3, 4, 5, 6, 7, 8, and 20 9 are views showing more clearly the construction and operation of some of the parts of my device.

A represents a shaft, on the outer end of which is secured the wind-wheel. This wind-wheel consists of a hub, B, from which extends 25 a series of radial arms, B' B'.

Pivots secured between the outer ends of the arms B' B' are a number of bars, C C, to which in turn are secured a series of inclined vanes, placed in such a position that when 30 they are parallel to the face of the wheel the wind, as it passes between them, will act to revolve the wheel, but when they are turned so as to be at right angles to the face of the wheel they will allow of the free passage of the wind, and the wheel will remain at a standstill. This is an old and well-known construction, and no part of my invention.

Extending downward from the bars C C are 35 lugs a a, to which are pivotally secured rods D D. The inner ends of the rods D D are attached to springs E E, which in turn are secured to the outer ends of a series of radial arms, F F. The arms F F are secured to the circumference or periphery of a brake-wheel, G, which is so journaled on the shaft A as to be allowed to have a free horizontal and revolving movement to the extent desired. The inner edge, b, of the circumference of the brake-wheel G is formed beveled at an angle of about 40 ninety degrees.

H is a brake-rod, which is provided at one

end with a brake-shoe, H', said brake-shoe being adapted to engage with the beveled portion b of the brake-wheel G. The other end of the brake-rod is provided with a hole, c, in 55 which a cord or wire, d, is secured for operating the brake. This cord or wire d passes downward through the hollow pitman of the engine.

I are a series of ratchet-teeth, which are 60 formed on the hub of the brake-wheel G. These ratchet-teeth are adapted to engage with ratchet-teeth J, formed on the inner face of the hub of the wind-wheel. (See Fig. 5.)

K is a crank-wheel, which is secured to the 65 inner end of the shaft A. The wrist e of this crank-wheel engages in a horizontal elongated slot or recess, f, formed in a head-piece, L, which is secured to the pitman M. Thus it will be seen that as the crank-wheel revolves 70 it will impart to the said pitman a vertical reciprocating motion only, which obviates the necessity of using a joint in the pitman-rod, which would otherwise be necessary. This construction is shown more clearly in Fig. 7 of 75 the drawings.

N represents the upper portion of my turn-table, which rests on a cap-piece, O. This upper portion, N, of the turn-table is provided with a shank, N', which is journaled at its upper end in the cap-piece O and at its lower end in a collar, P, said collar being provided with radial arms or rods g' g' g' g', which in turn are provided with screw-threads and extend through to the braces h' h' h' h', and act in connection 80 with nuts i' i' i' i' as a means whereby the lower end of the shank N may be adjusted so as to center it. (See Fig. 9.) The upper ends of the legs j j of the supporting-frame are secured together by means of the cap-piece O, which is 85 provided with depending plates k' k' k' k', which form recesses, into which the ends of the legs j j fit, and are secured by means of screws or bolts l l l l.

The operation of my device is as follows: 95 When the vanes are in the position shown in Fig. 1 the wind, when it strikes said vanes, will cause the wind-wheel to revolve. Now, if the wind is very strong and causes the wheel to revolve at too great a speed, the centrifugal 100 force will tend to bring the vanes to the position shown in Fig. 4, and thus allow the wind

to pass through without acting. As the wheel revolves slower the springs E E on the end of the rods D D will resume the normal position, (see Fig. 3,) thus bringing the vanes parallel to the face of the wheel, as shown.

When it is desired to stop the wheel it is only necessary to cause the shoe H' of the brake-rod H to engage with the edge b of the brake-wheel G. This will act to push the brake-wheel G toward the hub of the wind-wheel and cause the ratchets J J to engage, thus stopping the wheel. The engaging of the shoe H' with the brake-wheel G also acts to stop it to a certain extent. This will in turn cause the vanes to come to the position shown in Fig. 4. Thus when the wheel is stopped by the brake H' the vanes will be in such a position that the wind will not act on them.

What I claim is—

1. In a wind-engine, the combination, with

a series of pivoted vanes, of regulating-rods attached to said vanes at their outer ends and provided with springs at their inner ends, said springs in turn being secured to a brake-wheel, substantially as and for the purpose shown 25 and described.

2. In a wind-engine, the combination, with a brake-wheel, said brake-wheel being provided with ratchet teeth adapted to engage with ratchet-teeth secured to the wind-wheel, 30 of the springs and rods, the outer ends of said rods being pivotally secured to a series of vanes, substantially as and for the purpose shown and described.

In testimony whereof I have signed my name 35 to this specification in the presence of two subscribing witnesses.

Witnesses: CHARLES B. POST.

A. M. BEATTIE,
J. D. OLCOTT.
